INVENTOR

UNITED STATES PATENT OFFICE

95,790

DESIGN FOR A TWO-PIECE SLIP

Michael E. Awamy, New York, N. Y.

Application April 26, 1935, Serial No. 56,580

Term of patent 3½ years

To all whom it may concern:

Be it known that I, Michael E. Awamy, a citizen of the United States of America, residing in Manhattan, county of New York, and State of New York, have invented a new, original, and ornamental Design for a Two-Piece Slip, of which the following is a specification, reference being had to the accompanying drawing, forming part thereof, wherein,

The vertical lines on the skirt portion in Figures 1 and 2 represent an overlapping of the right and left sections of the slip, which are clasped together at its waist section.

I claim:

The ornamental design for a two-piece slip, substantially as shown and described.

MICHAEL E. AWAMY.
